(57) **CLAIM**

The ornamental design for a beverage shaker cup, as shown and described.

DESCRIPTION

FIG. 1 is a bottom rear left perspective view of a beverage shaker cup showing my new design, the bottom rear right perspective view being a mirror image thereof;
FIG. 2 is a right side elevational view, the left side elevational view being a mirror image thereof;
FIG. 3 is a front elevational view thereof;
FIG. 4 is a top plan view of both embodiments;
FIG. 5 is a rear elevational view thereof;
FIG. 6 is a front top left perspective view of a beverage shaker cup of both embodiments with the cup portion removed, leaving only the lid, for ease of illustration;
FIG. 7 is a rear top left perspective view thereof;
FIG. 8 is a rear left perspective view thereof;
FIG. 9 is a top front right perspective view thereof with the flip lid also removed for ease of illustration;
FIG. 10 is another bottom rear left perspective view of FIG. 1;
FIG. 11 is a bottom rear left perspective view of beverage shaker cup showing a second embodiment of my new design;
FIG. 12 is a rear elevational view thereof; and,
FIG. 13 is a left side elevational view thereof, the right side being a mirror image thereof.
